PIPE REAMER

Alexander H. Rowell, Pine Bluff, Ark.

Application November 17, 1955, Serial No. 547,438

1 Claim. (Cl. 131—246)

This invention relates generally to pipe reamers and is more particularly concerned with a mechanical pipe reaming device which operates and functions in substantially the same manner as a mechanical pencil sharpener.

A specific object of invention is to provide a support base including a bearing sleeve surrounding by a concentrically disposed support housing, the bearing sleeve having journaled therein a shaft member having one end secured to a crank member, the other end of which removably supporting a pipe reamer member in coaxial alignment with the shaft, and wherein the support housing removably supports a receptacle member having a material receiving portion underlying the reamer member and including an upper open portion for receiving a pipe bowl therein.

A further object of invention in conformance with that set forth above is to provide a mechanical pipe reamer adapted to accommodate a plurality of different reamer members.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a front elevational view of the novel mechanical pipe reamer;

Figure 2 is a sectional view taken substantially on line 2—2 of Figure 1 with portions shown in elevation;

Figure 3 is a perspective view of a reamer member usable in the device;

Figure 4 is a perspective view of another type reamer member usable in the device;

Figure 5 is a sectional view taken substantially on line 5—5 of Figure 4; and

Figure 6 is a fragmentary sectional view taken substantially on line 6—6 of Figure 1, showing details of the mounting of the receptacle member of the device.

The novel mechanical pipe reamer is indicated generally at 10 and includes a support assembly 12, a removable receptacle assembly 14, and a removable reamer blade assembly 16.

The support assembly 12 comprises a base member 18 containing suitable apertures for receiving fastening members such as the screws 20 for securing the base member on a generally horizontal support surface 22. The base member 18 has extending upwardly therefrom a vertical support portion 24 supporting a transverse tubular sleeve 26, said support element 24 incorporating a support housing 28 concentrically disposed about the tubular sleeve 26, the housing incorporating an annular housing 30 therearound which has a forward edge 32 terminating rearwardly of the forward edge 34 of the housing 28.

The tubular sleeve 26 has rotatably supported therein a shaft member 36, said shaft incorporating a forward annular flange 38 abutting the forward edge 40 of the sleeve 36, the rear end of the shaft 36 terminating in a reduced

2

diameter threaded portion as indicated at 42 and having disposed thereon a suitably apertured crank arm 44 by means of a retaining nut 46, said crank arm having secured on its outer end 48 a laterally extending handle portion 50.

As seen in Figure 6, the housing member 28 includes a pair of diametrically opposed laterally extending tab elements 52 which are forwardly disposed of the forward edge 32 of the annular housing portion 30 for accommodating therein a portion of the receptacle member as will subsequently become apparent. As seen in Figure 1, the tab elements 52 are disposed angularly relative to the vertical axis of the support element 24 for a purpose to become subsequently apparent.

The receptacle member 14 includes a pair of mutually parallel rear and front plate portions 54 and 56, respectively, each of which has flange portions 58 and 60, respectively, directed toward each other for supporting a substantially elliptical center portion 62, the portions 54 and 56 together with 62 defining a material receiving portion 64. The rear plate 54 incorporates an upper apertured portion 66 of the same diameter as the housing member 28, said aperture portion 66 being defined by an inwardly turned annular flange 68 extending around the housing member 28 when the receptacle member is mounted thereon. The annular flange 68 and the back plate 54 have extending therethrough diametrically opposed notched out portions 70, see Figure 1, the notched out portion 70 and the annular flange 68 extending along the arc of the flange 68 the same distance as the angular displacement of the tab elements 52 are displaced relative to the vertical axis providing an abutment portion 72 engageable with said tabs 52. Thus the receptacle member 14 is moved "longitudinally" upon the housing member 28 with the notched out portion 70 passing over the tabs 52 thereafter the housing member 14 is rotated counterclockwise as indicated by the arrow in Figure 1 with the abutment portion 72 engaging the tab portions 52 resulting in the receptacle member 14 having its longitudinal axis in alignment with the vertical axis of the support element 24.

The support element 24 includes a pair of forwardly extending rib or web portions 74 which are engageable with the outer surfaces of the plate member 54 for supplying additional support to the receptacle element 14.

The center portion 62 of the receptacle member has an upper cut out portion 76 which slopes downwardly from the rear to the front of the receptacle member, said opening 76 permitting the insertion of a pipe P therethrough. The forward plate 56 of the receptacle member includes an arcuate cut out portion 78 in substantial alignment with the housing member 28 of the support, this cut out portion permitting the bowl of the pipe to be moved longitudinally relative to the axis of rotation of the shaft 36.

The shaft 36 terminates beyond the collar portion 38 thereof in a reduced diameter threaded end portion 80 which removably receives thereon an internally tapped hub portion 82 of the reamer blade assembly 16. The hub has integrally secured thereon in longitudinal alignment with the axis of rotation of the shaft 36 a reamer blade portion 84 which is constituted by a plurality of relatively stiff wires defining a brush which has a rounded end portion 88, said reamer blade accommodating itself to the bowl of the pipe being reamed out.

As seen in Figure 4 another embodiment of reamer blade is indicated generally at 90, said blade including a hub portion 92 which is internally tapped as is the hub 82 of the previously mentioned reamer element, said hub 92 having integrally secured thereon a laterally extending and diametrically opposed blade element 94 which is tapered at its forward edge 96 accommodating it to the

shape of the bowl being reamed out, the blade being substantially flat as seen in Figure 5. Further observing Figure 5, it will be noted that the opposite edges of the blade 94 are sharpened on opposite side edges 96 and 98 whereby when the blade is rotated in the direction indicated by the arrow of Figure 5 each of the blade edges will be effective to ream out the pipe bowl.

As seen in Figure 3 a further reamer blade is indicated generally at 100 said blade including a hub portion 102 which is centrally apertured and threaded at 104 for accommodating thereon the threaded end 80 of the shaft 36, said hub having extending therefrom a pair of relatively parallel blades 106 and 108 which respectively include converging end portions 110 and 112 which are shaped to conform with the configuration of the pipe bowl being reamed out.

Various positional directional terms such as "front," "rear," etc. are utilized herein to have only a relative connotation to aid in describing the device and are not intended to require any particular orientation with respect to any external elements.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

A pipe reamer comprising a base, a vertical rear support on said base having an upper end provided with an

annular horizontal housing projecting forwardly therefrom and having a front edge, a surrounding housing on said horizontal housing flaring therefrom toward said front edge and having a front edge terminating in the rear of the front edge of said annular housing, an open top receptacle having a rear vertical plate, means on said plate adapted to suspend said receptacle from said annular housing comprising an annular flange on said rear plate fitting on said annular housing and on the front edge portion of the surrounding housing and defining an opening into which the front edge of the annular housing projects, a bearing sleeve on said support extending into said annular housing in concentric spaced relation thereto, a shaft journaled in said sleeve and provided with a crank on one end having a circumferential end thrust flange on its other end engaging said sleeve and provided with a forwardly extending reduced portion, and a pipe reamer member extending horizontally forwardly from said threaded portion into said receptacle and including a tapped hub portion threaded onto said reduced portion.
